INVENTOR

BY *Victor J. Evans*

ATTORNEY

J. Crawford
of a. Middleton.
WITNESS:

UNITED STATES PATENT OFFICE.

WARDEN G. CAMPBELL, OF MASON CITY, ILLINOIS.

BROODER.

Application filed June 9, 1922. Serial No. 567,085.

To all whom it may concern:

Be it known that I, WARDEN G. CAMPBELL, a citizen of the United States, residing at Mason City, in the county of Mason and State of Illinois, have invented new and useful Improvements in Brooders, of which the following is a specification.

This invention relates to improvements in houses for fowls and the like, the general object of the invention being to provide a movable partition for varying the size of the receiving compartment of the house so as to regulate the temperature therein.

Another object of the invention is to provide means for supporting the partition in its adjusted position.

This invention also consists in certain other features of construction and in the combination and arrangement of the several parts, to be hereinafter fully described, illustrated in the accompanying drawings and specifically pointed out in the appended claim.

In describing my invention in detail, reference will be had to the accompanying drawings wherein like characters denote like or corresponding parts throughout the several views, and in which:—

Figure 1 is a front view of a house constructed in accordance with my invention.

Figure 2 is an end view.

Figure 3 is a longitudinal sectional view.

Figure 4 is a transverse section.

Figure 5 is a fragmentary view of the rear of the device showing the ventilating means.

Figure 6 is a perspective view of one of the cross pieces 12.

Figure 7 is a perspective view of one of the doors.

In these views 1 indicates the side walls of the building which may be of any desired size and type, the walls being formed with the usual doors and windows, though I prefer to provide the doors with wooden parts 2 and parts 3 formed of galvanized iron and wire mesh, the parts 2 sliding in grooves in the door frame and operated by chains 4 so that the door openings may be entirely closed by the galvanized iron part and the wooden part or left open with the open part covered by the screen.

The floor 5 is movably supported by the

chains 6 which are connected to the corners of the floor and pass over suitable pulleys 5 to a shaft 8 which is rotatably supported in the building and is provided with a handle 9 for rotating it and with ratchet mechanism 10 for preventing retrograde movement thereof. 55 60

By this arrangement of parts the floor can be raised and lowered so as to vary the space within the building and thus regulate the temperature. For instance, on a cold night the floor would be raised to make the space occupied by the chickens small so that the heat from the bodies would hold the restricted space at the proper temperature. During the day the floor would be lowered so as to give the chickens more room and to lower the temperature by increasing the space to be heated. 65 70

Besides the ratchet means I may provide means for holding the floor in adjusted position, such means consisting of racks 11 75 placed along the walls and cross pieces 12 having beveled ends for engaging the rack teeth and upon which the floor rests when said pieces are in position.

The invention may be used with heated buildings, as shown in the drawings. The lamp is shown at 13 and is pivotally supported in the support 14. The chimney 15 of the lamp extends into an elbow 16. A pipe 17 connects this elbow with a heating drum 18 and a pipe 19 leads from the drum to the outside of the building. A damper 20 is placed in the pipeline to control the passage of heat. The drum must be placed above the highest point that the floor is to 90 occupy so that said drum will always remain in the occupied space. 80 85 90

I may also provide ventilating means for the device and in this case the building is provided with air holes 22 which are 95 located above the highest point which the floor will reach and a gate 23, having perforations therein, is adapted to control the passage of air through said holes.

It is thought from the foregoing description that the advantages and novel features of my invention will be readily apparent.

I desire it to be understood that I may make changes in the construction and in the combination and arrangement of the several

parts, provided that such changes fall within the scope of the appended claim.

What I claim is:—

A building of the class described comprising a vertically movable floor, a shaft, means for rotating the same, chains connecting the shaft with the floor and means for holding

the floor in adjusted position, such means consisting of vertically arranged racks and cross pieces having beveled ends for engaging the racks and upon which the floor rests. 10

In testimony whereof I affix my signature.

WARDEN G. CAMPBELL.
